FLAPPING WING TOY

William Eugene Folk, Shreveport, La.

Application June 10, 1949, Serial No. 83,229

1 Claim. (Cl. 46—124)

1

This invention relates to a toy, and more particularly to a mechanical toy device which includes wings or arms that oscillate, the oscillation of the wings or arms being controlled by a pair of handles.

The object of the invention is to provide a toy that includes a pair of handles which have a pair of wings connected thereto, there being a spring clamp interconnecting the handles together whereby upon movement of the handles the wings will be caused to flap or oscillate by alternately applying and releasing pressure on the handles, there being a means for transmitting pressure from the handles to the wings.

Still another object of the invention is to provide a toy which includes wings that flap, whereby the toy will resemble butterflies, birds, bats or other fanciful objects, the toy of the present invention being adapted to be carried in a person's hand or mounted on a suitable structure.

A still further object of the invention is to provide a mechanical toy which includes a relatively simple but sturdy handle support which insures that there will be an efficient spring action with very little friction between the moving parts.

A further object of the invention is to provide a mechanical toy device which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a front elevational view of the toy device of the present invention, showing the handles in one position, and with parts broken away and in section.

Figure 2 is a side elevational view of the toy of the present invention.

Figure 3 is a sectional view taken on the line 3—3 of Figure 2.

Figure 4 is a view similar to Figure 1, but showing the handles in another position.

Figure 5 is an elevational view showing the wing construction.

Figure 6 is a sectional view taken on the line 6—6 of Figure 5.

Figure 7 is a front elevational view of the wings.

Figure 8 is a view showing certain constructional details of the present invention.

Figure 9 is a plan view showing one of the wings.

Figure 10 is a plan view of the other wing.

2

Referring in detail to the drawings, there is shown a mechanical toy device which may be fabricated of any suitable material, and the toy of the present invention is adapted to simulate a fanciful object such as a butterfly, bird, bat or the like. The toy comprises a pair of handles 20 and 21. The handles 20 and 21 have the same construction. Thus, the handle 20 includes an end portion 25 and a jaw 26, the jaw 26 being offset with respect to the end portion 25. The other handle 21 includes an end portion 24 and a jaw 19, and the end portions 24 and 25 are adapted to be gripped in the user's hand.

The handle 21 is further provided with a recess 15 or cutout 27 which is arranged in facing relation with respect to a recess 28 in the other handle. A U-shaped spring member 22 interconnects the handles 20 and 21 together, and the spring member 22 includes a pair of spaced apart legs 18 which are seated in the recesses 27 and 28.

Extending from the jaw 25 is a pair of spaced parallel eye supports 16 and 17, while extending from the other jaw 26 is a similar pair of spaced parallel eye supports 29 and 30. The eye support 16 has an opening which registers with an opening in the other eye support 17, and similarly, the eye supports 29 and 30 have openings which register with each other. Extending through the registering openings in the eye supports 16 and 17 is a securing element 31 which may be a pin or bolt. A similar securing element 32 extends through the registering openings in the other pair of eye supports 29 and 30. It will be seen from Figure 8 of the drawings that the registering openings in these eye supports are larger than the diameter of the securing elements 31 and 32 so as to provide sufficient play in order to permit the present invention to operate without jamming. The securing elements 31 and 32 move towards and away from each other as the handles 20 and 21 are reciprocated.

The toy of the present invention further includes a pair of movable wings 33 and 34. The wing 33 includes a web 35 and a pair of spaced parallel arms 36 and 37 extend from the web 35 formed integral therewith. The other wing 34 includes a web 38 and a pair of spaced parallel arms 39 and 40. Extending from the arm 37 is a pair of spaced parallel bearing supports 41 and 42, while extending from the arm 36 is a pair of bearing supports 43 and 44. Also, the arm 40 is provided with a pair of apertured bearing supports 47 and 48, and a pair of bearing supports 45 and 46 extend from the arm 39.

Each of these bearing supports is provided with an opening, for the passage therethrough of the securing elements 31 and 32, and for the passage therethrough of a pivot bolt 48.

From the foregoing, it is apparent that a mechanical toy has been provided wherein the wings 33 and 34 will be given an oscillatory motion upon actuation of the handles. In use, the end portions 24 and 25 of the handles are manually pressed together and this causes the jaws 19 and 26 to move apart about the pivot spring 22. Thus, the parts move from the position shown in Figure 1 to the position shown in Figure 4. This places tension on the spring 22 and the wings 33 and 34 move apart as shown in Figures 4, 6 and 7. During this movement, the bolt 49 moves to a lower position (i. e. closer to the handles 29 and 21). When the pressure is released on the handles 28 and 21, the spring 18 causes the jaws 26 and 27 to quickly close or move toward each other and this forces the wing sections 33 and 34 to their raised position. The securing element 31 extends through the registering openings in the eye supports 16 and 17, and also through the apertured bearing supports 43 and 42. Similarly, the other securing element 32 extends through the registering openings in the eye supports 29 and 30, and through the apertured bearing supports 46 and 48. The pivot bolt 49 extends through the registering bearing supports 41, 44, 45, and 47. The distance between the bearing supports 47 and 48 is slightly greater than the distance between the bearing supports 45 and 46. Also, the distance between the bearing supports 41 and 42 is slightly greater than the distance between the bearing supports 43 and 44.

The shape of the wings 33 and 34 can be varied to simulate various objects, and the U-shaped spring 22 serves as the closing force for the handles. Also, the spring 22 serves to maintain the handles secured together, and gives a rigid support to prevent any twisting of their handles from the normal position. The bearing supports are preferably integral with the wings and these parts are made of sufficient thickness to provide the required strength.

I claim:

A mechanical toy device simulating a fanciful object comprising a pair of handles, each of said handles including an end portion adapted to be gripped in the user's hands, the other end of each of said handles terminating in a jaw, said jaws being offset with respect to said end portions, there being a countersunk recess arranged in each of said end portions, said recesses being arranged in facing relation with respect to each other, a U-shaped spring member interconnecting said handles together and including a pair of spaced apart legs seated in said recesses, pairs of eye supports arranged on each of said jaws, said eye supports being provided with registering openings, a securing element extending through each pair of eye supports on each of said jaws, said securing elements being mounted for movement toward and away from each other upon actuation of said handles, a pair of movable wings operatively connected to said securing elements, each of said wings including a web, and a pair of spaced parallel arms extending from said web, a first and second bearing support extending from each of said arms, there being an opening in each of said bearing supports, said securing elements passing through said openings in the first supports and a pivot bolt extending through the openings in the second supports.

WILLIAM EUGENE POLK.
